UNITED STATES PATENT OFFICE.

GEORGE H. HULETT, OF AKRON, OHIO, ASSIGNOR OF ONE-HALF TO WEBSTER, CAMP AND LANE MACHINE COMPANY, OF SAME PLACE.

LOADING OR UNLOADING APPARATUS.

SPECIFICATION forming part of Letters Patent No. 679,967, dated August 6, 1901.

Application filed May 11, 1901. Serial No. 59,757. (No model.)

To all whom it may concern:

Be it known that I, GEORGE H. HULETT, of Akron, in the county of Summit and State of Ohio, have invented certain new and useful Improvements in Loading or Unloading Apparatus; and I do hereby declare the following to be a full, clear, and exact description of the invention, such as will enable others skilled in the art to which it appertains to make and use the same.

My invention relates to an improvement in loading and unloading apparatus, and more particularly to means for use in unloading boats, one object of the invention being to provide means for the purpose stated which shall be so constructed as to reach ore or coal under the deck and in remote parts of the hold and receive the ore or coal for conveying the same from the boat to cars or other places for discharging the material.

A further object is to so construct a bucket for use with an unloading apparatus that it can be operated first to gather ore or coal from points more or less remote from the hatchway through which the supporting and carrying means for the bucket depend and then scooping the ore or coal so gathered.

A further object is to so construct a combined scoop and gatherer that when operating to perform its functions as a scoop it will occupy no more space than would the scoop alone without the gathering device.

A further object is to provide means for the purpose stated which shall be simple in construction, compact, easy to operate, and which shall be effectual in all respects in the performance of their functions.

With these objects in view the invention consists in certain novel features of construction and combinations and arrangements of parts, as hereinafter set forth, and pointed out in the claims.

In the accompanying drawings, Figure 1 is a view showing an embodiment of my invention. Fig. 2 is a view showing the bucket open and the telescopic section of one of the buckets constituting the gatherer. Fig. 3 is a view showing the buckets closed. Fig. 4 is a sectional view of the telescopic bucket.

50 A represents a boat, and B a hollow de-

pending leg carried by any suitable apparatus—such, for instance, as is shown and described in Letters Patent granted to me June 26, 1900, and designated by No. 652,313—and said leg carries at its lower end the 55 buckets or scoops 1 2. The leg B is revolvably mounted and operated as shown in my said patent. The bucket or scoop 1 is hinged to the lower end of the leg, approximately in line with the wall of the latter, while the 60 bucket 2 is pivoted to the outer end of the horizontally-projecting bracket 6, so that the bucket 2 can be projected under the decks, as will be more fully hereinafter explained. Both buckets or scoops are pivotally connected by links 7 with the lower end of the piston-rod 8 of a hydraulic or other motor 9, so that when said piston is raised the buckets 65 will be moved to a closed position and that by dropping the piston-rod the buckets 70 will be opened.

The bucket 1 is preferably made angular in cross-section, open at its top 10 and one side 11, the latter alining with the corresponding open side 12 of the bucket 2 when the 75 buckets are closed to form, in effect, one bucket. The bucket 2, which, as before stated, is a combined bucket and scraper or gatherer, comprises the main body portion or shell 13, open at its sides 12, 14, and 15, and 80 a telescopic member or shell 16, which forms the scraper or gatherer. A hydraulic or other cylinder 17 is located within the body portion 13 of the bucket 2, alongside the inner wall 18 thereof. A piston is located in this cylinder, 85 and the rod 19, projecting from this piston, extends to the far end of the shell or member 16, where it is secured thereto, the cylinder 17, with its piston and piston-rod, constituting a motor (which can be controlled by 90 any suitable valve mechanism and receive motive power from any convenient source) for moving the telescopic shell or member outwardly and inwardly for scraping or gathering ore or coal from points distant from the 95 hatchway through which the depending leg projects. When the shell or member 16 is disposed within the body portion 13, the wall 21 of the gatherer will constitute one wall of the bucket, and this wall will form the bottom of 100

the bucket when the latter is closed against the bucket 1. The cylinder 17 is protected from the ore or coal by means of a guard-plate 22, secured to the body-shell 13, and the piston-rod 19 is similarly protected by a guard-plate 23, secured to the shell or member 16 and disposed in a parallel plane with the guard 22, so as to move under it when the shell or member 16 is drawn within the body portion 13. When the shell or member 16 is projected and operated to scrape or gather the ore or coal, more or less lateral strain will fall upon the connection of said shell with the main shell or body portion of the bucket. In order to withstand this strain and at the same time permit the free movements of the telescopic shell or gatherer 16, the devices now to be described may be employed. Antifriction-rollers 24 are mounted on short shafts 25, located at the end 15 of the body-shell 13 and run against shoulders 26 on the inner shell or gatherer 16, said shoulders being formed by depressing the corners of said shell or gatherer. A bar 27 is secured to the inner face of each side wall of the body-shell 13, and these bars constitute trackways for antifriction-rollers 28, carried by the telescopic shell or gatherer 16, said rollers being located between the bars or trackways 27 and the rollers 24. The free edges of the side walls of the telescopic shell or gatherer slide freely in guideways 29, formed by the ends 30 of the telescopic shell 16 and a plate 31, parallel therewith, the parts 30 31 being spaced apart by a bar 32 and secured together by means of bolts 33. A stiffening - plate 34 is secured within the ends 30 of the shell 16 and secured in place by the bolts 33.

From the construction and arrangement of parts above described it will be seen that the telescopic shell or gatherer can be readily moved by the hydraulic motor to gather the ore or coal out of reach of buckets as heretofore constructed and that binding effect of lateral strain will be obviated. By rotating the depending leg the buckets carried thereby can be made to project in any direction and the telescopic gatherer can be projected far under the decks and operated to draw the ore and coal in position where it can be readily scooped by the buckets. By my improvements I am enabled to reach ore or coal located centrally between hatchways, as well as such as might lie in corners far removed from the hatchway.

My improvements are simple in construction and will be found in practice to perform in an effectual manner the functions for which they are intended.

Various slight changes might be made in the details of construction of my invention

without departing from the spirit thereof or limiting its scope, and hence I do not wish to confine myself to the exact details of construction herein set forth.

65

Having fully described my invention, what I claim as new, and desire to secure by Letters Patent, is—

1. In an unloading apparatus, a bucket comprising telescopic shells, and means for moving one of said shells relatively to the other.

2. In an unloading apparatus, the combination of two shells comprising a combined bucket and gatherer, and means for moving one of said shells relatively to the other.

3. In an unloading apparatus, the combination with a shell having three open sides, of a shell having two open sides and constructed to telescope within the first-mentioned shell, one wall of the telescopic shell constituting a scraper when moved relatively to the first-mentioned shell, and also constituting a bottom for said first-mentioned shell when the telescopic shell is disposed therein.

85

4. In an unloading apparatus, the combination with a revoluble leg, of a combined bucket and scraper or gatherer carried thereby and comprising telescopic shells and means for moving one of said shells relatively to the other.

5. In an unloading apparatus, the combination with a support, of two buckets hinged thereto, one bucket comprising telescopic members, means for moving one of said members relatively to the other and means for closing said buckets together to form a scoop.

95

6. In an unloading apparatus, the combination of two shells comprising a combined bucket and gatherer, and a motor secured within one shell and connected with the other shell.

7. In an unloading apparatus, the combination of two shells, one telescoping within the other and comprising a combined bucket and scraper or gatherer, rollers mounted within one shell and bearing against the other shell, trackways secured to the first-mentioned shell and rollers carried by the telescoping shell between said trackways and first-mentioned rollers and bearing on said trackways.

8. In an unloading apparatus, the combination of two shells comprising a combined bucket and gatherer, and guideways for the respective sides of one shell within the other.

115

In testimony whereof I have signed this specification in the presence of two subscribing witnesses.

GEORGE H. HULETT.
